CLAIM

The ornamental design for the accessory compartments for a golf bag, as shown and described.

DESCRIPTION

FIG. 1 is a perspective view of the golf bag accessory compartments showing my design;

FIG. 2 is a front view of the golf bag accessory compartments showing my design;

FIG. 3 is a side view of the golf bag accessory compartments showing my design;

FIG. 4 is a top view of the golf bag accessory compartments showing my design;

FIG. 5 is a bottom view of the golf bag accessory compartments showing my design;

FIG. 6 is a perspective view of the golf bag showing one compartment removed; and,

FIG. 7 is a rear view of the removed compartment in FIG. 6.

The broken line portions of the disclosure are for illustrative purpose only and form no part of the claimed design.
